GARMENT HANGER

Maurice Cohen, 3580 NW. 52nd St., Miami, Fla.

Filed July 16, 1956, Ser. No. 598,086

1 Claim. (Cl. 211—124)

The present invention relates to a garment hanger for displaying men's trousers or the like. More particularly the present invention relates to a garment hanger of the pivotal two-point suspension type which includes a clip construction that is adapted to positively retain a pair of trousers in position on the hanger.

The pivotal two-point suspension hanger has been used for some time with garment display fixtures and has been employed particularly with those fixtures that are adapted to display men's trousers. This type of hanger is generally formed with a horizontal supporting bar and includes an inclined bar formed integral with the supporting bar. The inner ends of the supporting bar and inclined bar are spaced apart and are provided with inturned projections that are received by appropriate openings in a supporting bracket, fixture or the like. These heretofore known pivotal two-point suspension type hangers were usually provided with some form of retaining clip at the outer end thereof for retaining the trousers in position. However, these prior known retaining clips have been found to be objectionable since they exerted undue pressure on the trouser fabric thereby causing damage due to marking and indentation. Moreover, the trouser fabric in contact with the clips was subjected to considerable wear due to rubbing and sliding of the trousers thereover. This wear was particularly apparent if the trousers were moved to various positions on the supporting bar frequently, which normally occurred when the trousers were handled during the display thereof.

Furthermore, when a plurality of the heretofore known two-point suspension type hangers which included the conventional retaining clips were pivotally mounted adjacent to each other, pivotal movement of the hangers individually or together resulted in considerable wear of the trouser fabric when the clip structure which projected from one hanger rubbed against the fabric of the trouser suspended on the adjacent hanger. This wear was aggravated by the fact that during this pivotal motion, the protruding hanger clip moved against the fabric of the trouser on the adjacent hanger in a direction parallel to the axis of the horizontal supporting bar of the adjacent hanger thereby resulting in an increased rubbing action of metal against fabric.

It is thereby an object of the present invention to provide a garment hanger that positively retains the garment being displayed thereon without resulting in undue wear of the garment fabric.

Another object of the present invention is to provide a garment hanger which is formed with a clip structure thereon, the clip being adapted to positively retain trousers on the hangers without causing undue wear of the trouser fabric and to occupy as small an area as possible in order to provide a maximum of space for the display of merchandise.

Still another object of the present invention is to provide a garment hanger which is formed with a clip

2

thereon that is adapted to positively retain trousers on the hanger without causing undue wear of the trouser fabric, due to rubbing, etc.

Still another object of the present invention is to provide a garment hanger of the pivotal two-point suspension type which includes a simple yet unique clip structure that not only positively retains the garment on the hanger but cooperates with the garment to present a neat and an attractive display.

10 Other objects and the nature and advantage of the instant invention will be apparent from the following description taken in conjunction with the accompanying drawings, wherein:

Fig. 1 is a perspective view of several hangers of the pivotal two-point suspension type embodied in the present invention, the hangers being shown mounted on a bracket that is illustrated in fragmentary form.

Fig. 2 is an elevational view of the hanger embodied in the present invention showing one form of the clip retaining structure,

Fig. 3 is an elevational view of hanger embodied herein showing another form of the clip that is joined to the outer end of the hanger,

Fig. 4 is a vertical sectional view of the hanger shown in Figs. 1 and 2 illustrating one position of the trousers being displayed with respect to the hanger clip structure; and

Fig. 5 is a vertical sectional view of the hanger shown in Figs. 1 and 2 illustrating another position of the trousers with respect to the clip structure and showing a second pair of trousers being positioned on the trousers that are retained by the clip.

Referring now to the drawings and particularly to Figs. 1 and 2, the hanger embodied in the present invention is illustrated and includes a supporting bar 10 and an inclined bar 12. The supporting bar 10 and inclined bar 12 define the members of a two-point suspension type hanger and are joined at the outer end thereof by a clip structure generally indicated at 14. The supporting bar 10 is formed with an integral inturned projection 16, and similarly the inclined bar 12 is formed with an integral inturned projection 18. The hanger is mounted in position on any convenient rack or bracket, one form of which is shown in Fig. 1. The bracket illustrated in Fig. 1 includes an upper beam 20 and a lower beam 22, the beams 20, 22 being suitably secured to a supporting frame 24. A similar frame (not shown) is provided for the other ends of the beams 20, 22 and the supporting frames may be mounted on a wall installation or be formed as part of a mobile floor unit. It is understood, of course, that the two-point suspension hanger described herein may be mounted on any conventional type of trouser or pants rack such as the commonly known rectangular rack, or it may be utilized with the new type of circular rack such as illustrated in applicant's Patent No. 2,701,646 granted February 8, 1955. As shown in Fig. 1, the inturned projections 16, 18 are received by suitably positioned openings in the upper and lower beams 20, 22. The hangers are thereby mounted for convenient pivotal movement which is necessary when displaying trousers on the hangers.

In order to firmly retain a pair of trousers on the hanger embodied herein, the novel clip structure 14 is employed. The clip structure 14 includes a bar, one form of which is indicated at 26 in Fig. 2. The bar 26 is secured by brazing or spot welding to a shortened vertical portion 28 that is integrally joined to the supporting rod 10 and inclined rod 12. The bar 26, rod 10 and inclined rod 12 all lie substantially in the same plane, whereby when the trousers to be displayed on the hanger are clasped by the clip structure 14, the

clasped material necessarily follows a circuitous path and is thus firmly retained in position on the hanger.

Referring now to Figs. 1 and 4, the trousers to be displayed are indicated generally at 30 and are draped over the supporting rod 10 in the conventional manner, the leg and waist portions hanging downwardly, and being indicated at 32, 34 respectively. With the trousers 30 draped over the supporting rod 10, the trousers are secured on the hanger by moving them forwardly toward the clip structure 14, the leg position being moved behind the bar 26. This causes the fabric defining the leg portion 32 to engage the fabric defining the waist portion 34. The bar 26 is spaced sufficiently from the rods 10 and 12 to eliminate any undue pressure on the fabric by the metal parts and thereby reduces wear on the fabric. The fabric defining the leg portions 32 follows the circuitous path around the bar 26 and by reason of the fabric to fabric contact, the trousers are firmly retained in position on the supporting rod 10. It is seen therefore that by providing the clip structure as described there is no metal to fabric to metal pressure which is normally present in the prior known trouser retaining clips and thus the trousers clasped by the clip embodied herein will not be marked or be unduly worn as the trousers are constantly shifted in position during the display thereof. The fabric against fabric contact induced by the arrangement of the bar 26 provides maximum friction and prevents the trousers from sliding or moving in position on the rod 10.

Since the elements of the clip 14 all lie in the same plane, the waist portion 34 as seen in Fig. 5 may be position behind the bar 26, it being understood that the clasping action is the same as described above in connection with Fig. 4.

It is sometimes desirable to display more than one pair of trousers on a single hanger and the hanger described herein is particularly adapted for this purpose since there is no unwieldly or space consuming clip structure formed on the hanger. As illustrated in Fig. 5, a second pair of trousers indicated at 36 is draped over the trousers 30 and due to the friction of the fabric to fabric contact the second pair of trousers will be firmly retained in position. It is seen that a second pair of trousers may be slipped around the clip bar in conjunction with and exactly in the same manner as the first pair of trousers without exerting undue pressure or wear or rubbing of the trouser fabric due to metal to metal pressure, since retention is accomplished by causing one member of the trousers to follow the curvature of the clip bar and therefore frictionally engage the other member of the trousers.

Referring now to Fig. 3 a modified form of the clip structure is illustrated and is indicated generally at 40. The clip structure 40 is formed as an integral unit with the hanger members 10 and 12 and includes a bar 42 that is bent double the ends of which are integrally joined to the rods 10 and 12. The function of the double bar clip structure 40 is identical to that of the clip structure 14 as described above and acts to positively retain a pair of trousers in position on the supporting rod 10 of the garment hanger.

Further modification of the clip structure includes the garment hanger shown in Figure 3, with a 90 degree twist of the integral double bar clip about a common horizontal axis, which axis would lie in the same plane as all the members making up said hanger. This would

tend to increase the frictional engagement of the trouser fabric adjacent to the clip.

It is seen that the garment hanger embodied herein includes a simple yet unique clip arrangement that not only firmly retains the trousers in position on the hanger but also presents a neat appearing arrangement. The clip structure enables the trousers to be positioned on either side of the clip bar and in this position the trouser leg and waist portions make fabric to fabric contact for maximum function. There is no metal to fabric to metal pressure and thus the fabric is not squeezed between metal parts. Damage due to marking and wear is thereby avoided. The hanger using the clip structure described above is simple to manipulate and since the cumbersome conventional clip is eliminated, the trousers are displayed to their best advantage.

It is furthermore seen that when trousers are displayed on the hangers described herein in the manner described above, the resultant appearance is one of clean line and form and that when a plurality of the garment hangers are mounted adjacent to each other, a minimum portion of the hanger is seen while a maximum of the fabric is seen which is highly desirable in garment display.

It will be obvious to those skilled in the art that various changes may be made without departing from the spirit of the invention and therefore the invention is not limited to what is shown in the drawings and described in the specification but only as indicated in the appended claim.

What is claimed is:

In a garment hanger, a generally horizontal upper rod for supporting trousers thereon, an inclined lower rod, a clip structure joined to said horizontal upper rod and to said inclined lower rod at the outermost ends thereof, said inclined lower rod defining a supporting member for absorbing the loads carried by said upper rod, projections formed on the innermost ends of said horizontal and inclined rods for engaging a supporting structure thereby pivotally mounting said garment hanger on said supporting structure, said clip structure including a short vertical portion and a clip bar joined to said short vertical portion and extending inwardly a distance equal to a portion of said upper horizontal rod and located in spaced parallel relation with respect thereto, said clip bar and upper and lower rods being disposed in substantially the same vertical plane so that a portion of said trousers suspended from said horizontal upper rod is forced around said clip bar, the curvature of the fabric around said clip bar causing the material adjacent said clip bar to make fabric-to-fabric contact for firmly retaining said trousers on said hanger.
